ORVILLE C. MANN, OF OAK PARK, ILLINOIS.

SMOKE-JACK FOR ROUNDHOUSES.

1,176,075.

Specification of Letters Patent. Patented Mar. 21, 1916.

Application filed October 8, 1914. Serial No. 865,660.

To all whom it may concern:

Be it known that I, ORVILLE C. MANN, a citizen of the United States, residing at Oak Park, in the county of Cook and State 5 of Illinois, have invented new and useful Improvements in Smoke-Jacks for Round-houses, of which the following is a specification, reference being had to the accompanying drawings, forming a part thereof.

10 The purpose of this invention is to provide an improved device in the nature of a smoke jack for round houses, having novel features for improving the draft for the locomotive served by the smoke jack and diminishing the draft by which the warm 15 air might be drawn out of the round house, and for other minor purposes.

It consists in the elements and features of construction shown and described as indicated in the claims.

In the drawings: Figure 1 is a longitudinal vertical section of a smoke jack embodying this invention. Fig. 2 is a transverse vertical section of the same. Fig. 3 is an elevation of a fitting employed in the construction, the adjacent parts being shown in dotted line in their relative positions with respect to said fitting. Fig. 4 is an elevation of the same fitting looking in the direction of the arrow, 4, on Fig. 3. Fig. 5 is a view similar to Fig. 1, showing a modification.

The smoke jack shown in the drawings has the usual form in general of smoke jacks 35 for round houses, comprising the customary discharge stack member, 1, mounted above the round house, the customary stack member, 2, mounted within the round house and discharging into the lower end of the member, 1, and the flaring intake mouth-piece or hood, 3, at the lower end of the member 2, under which the stack of the locomotive to be served by the jack is positioned for discharging its smoke into said hood and up 40 through the members, 2, and 1, of the jack. The receiving mouth or hood, 3, is oblong in horizontal dimensions at its lower end, being slightly tapered upwardly in transverse plane to meet the dimension of the lower 45 end of the member, 2, of the stack, and be- ing much more tapered upwardly in longitudinal vertical plane to similarly meet the dimension at the lower end of the said member, 2, at the upper end of said hood. The side walls, 4, 4, of the hood, 3, extend lower 50 than the end walls, 5, 5, of said hood, being outwardly flared at the lower end as to the excess of their length beyond the length of said end walls, forming flanges, 4^a, 4^a, between which the locomotive stack passing 55 under the ends of the end walls advances to position. Both the end walls and side walls are terminated at their lower edges by outwardly and upwardly-turned flanges forming drip troughs, 4^b and 5^b, on said side 60 walls and end walls, respectively. Fittings, 6, are provided which are applied to the outer surfaces of the side walls, 4, 4, along the end edges of the flange portion, 4^a, and extending up beyond the angles between 65 said flanges and the upper portion of said side walls to stiffen said angles and to afford means for attaching supporting hanger rods, 7, by which the stack is suspended 70 from the round house roof, (represented as 75 to its position by the line, 8). These fittings, 6, extending along the ends of the flanges, 4^a, and down into the drip troughs, 4^b, form end closures for the drip troughs. Each of said fittings is further provided 80 with a conduit, 9, rigid with the fitting, and extending through the flange or web of said fitting which forms said end closure in an oblique direction so that the upper end of said conduit is presented under the adjacent end of the drip-trough, 5^b, of the adjacent end wall so that it may receive 85 outside the web of the fitting in which it is mounted, the drip from said drip-trough, while the lower end of the circuit overhangs 90 the drip-trough, 4^b, of the side wall. By this means the drip from the shorter end walls is delivered from the end wall drip-troughs down into the lower side-wall drip-troughs. For taking care of the drip from the inner 95 surface of the jack, flanges, 4^c and 5^c, are riveted onto the inner surfaces of the side and end walls, respectively, the flanges, 4^c, on the side walls being sloped toward the middle of the width of said side walls for 100

discharging the drip through an aperture, 4^a, into the outer drip-trough, 4^b, of said side walls. The flanges, 5^b, forming drip-troughs on the end walls, are extended 5 through apertures, 4^c, in the side walls so that they also discharge into the outer drip-troughs, 4^a, of said side walls. Said side-wall drip-troughs are drained by discharge pipes, 4^d, at the middle point of their length.

10 The chief purpose of this invention is to provide means for restricting the draft through the jack stack as nearly as possible to the locomotive smoke stack so that not only will that draft be as efficient as possible, but also the jack will be prevented from drawing the warm air from the round house outside the locomotive. For this purpose, in the construction shown in Figs. 1 and 2, there is provided an up-and-down partition, 10, extending transversely of the hood, 3, being pivotally mounted at 12, mid-way in the longitudinal dimension of the lower mouth of the hood, said partition extending from its said pivoted lower end up substantially to the lower end of the straight up-take member of the jack stack,—that is, to the upper end of the tapering hood. This partition is wide enough to extend from side-wall to side-wall of the stack with only 30 sufficient looseness of fit to make it free to rock over its fulcrumed lower end to swing its upper end from one side to the other of the upper end of the hood,—that is, from the full-line position shown in Fig. 1 to the 35 dotted-line position in that figure. It will be seen that at one of these positions of the partition, 10, the hood will conduct the smoke from a locomotive stack positioned under the right-hand half of the elongated 40 lower mouth of the hood into the straight up-take portion of the jack stack, excluding air drawn from the round-house from the left-hand half of said mouth while at the other position it will similarly conduct the 45 smoke from a locomotive stack positioned under the left hand half of the mouth to the exclusion of air drawn from the round-house through the right-hand half.

For positioning the partition, 10, in one 50 position or the other, it is provided near the upper end with operating link-rods, 13, 14, extending out respectively through the opposite end walls, 5, 5, of the hood, one of said rods, as the rod, 13, being connected 55 with a chain, 15, extending over a pulley, 16, and carrying a weight, 17, sufficient to start the partition from its leaning position shown in full line so as to cause it to rock over to the opposite leaning position 60 shown in dotted line in Fig. 1. The other rod, 14, is connected by a chain, 18, extending over a pulley, 19, down to a position where it may be operated to engage it with either one of three hooks, 20, for holding

the partition at either of said leaning positions or at vertical position intermediate the two, as may sometimes be desirable.

In the modification shown in Fig. 5, the partition there indicated by the numeral, 21, instead of being fulcrumed at its lower end, is suspended freely on two horizontal rods, 22, 22, extending from end-wall to end-wall of the hood at a level considerably above the center of gravity of the partition, said rods having each two stops, 23, between which the partition is lodged and suspended upon the rods, said stops being at such position on the rods, 22, that when the operating rods, 13 and 14, are operated to draw the upper end of the partition over to either 75 leaning position shown in Fig. 1, the partition stopped against said stops is forced into inclined position, substantially the same as that which it would occupy if fulcrumed at its lower end, as in Fig. 1. In this construction it will be seen that the partition will remain vertical throughout any range of movement laterally caused by the rods, 13, 14, until it strikes the stops.

I employ with this jack the same form of 90 stack member, 1, mounted above the roof as shown in my Patent No. 826,864 dated July 4, 1906, having tubes, 25, leading from the space under the roof of the round-house outside the stack-member, 2, into the exterior 95 stack-member, 1, for ventilating the upper space of the round-house of the roof and causing that ventilation to assist the draft through the stack while at the same time furnishing warm air from the round house 100 to prevent the outer member, 1, from causing excessive condensation of moisture from the locomotive discharge during the first few minutes of use before the locomotive discharge itself has time to warm said outer 105 section.

I claim:

1. In a smoke-jack for round-houses, in combination with a downwardly open jack-stack having a flaring receiving mouth or 110 hood and an up-and-down partition in such flaring mouth mounted therein for movement of its upper end from one side to the other of the narrow upper end of the hood.

2. In a smoke-jack for round-houses, in 115 combination with a fixed jack-stack whose lower receiving end consists of a downwardly open flaring hood for overhanging the locomotive stack to be served; an up-and-down partition supported in said flaring mouth-piece for movement of its upper end to either side of the smoke passage, and means for so moving it at will.

3. In a smoke-jack for round-houses, in combination with a fixed jack-stack whose 125 lower receiving end consists of a downwardly widening or flaring hood for overhanging the locomotive stack to be served;

an up-and-down partition pivoted below its center of gravity for rocking its upper end to either side, and means engaging it near the upper end for so rocking it.

5 4. In a smoke-jack for round-houses, in combination with a fixed jack-stack whose lower receiving end comprises a downwardly flaring hood or mouth-piece for overhanging the locomotive stack to be served; an up-and-down partition supported within said hood for movement of its upper end from side to side of the smoke passage; links connected to said partition extending out through the opposite end walls of the hood, and means for operating said rods endwise.

5. In a smoke-jack for round-houses, in combination with a fixed jack-stack whose lower receiving end comprises a downwardly-flaring hood or mouth-piece for overhanging the locomotive stack to be served; an up-and-down partition supported within said hood for movement of its upper end from side to side of the smoke passage; links connected to said partition near the upper end, extending out through the opposite end walls of the hood; a weight and a flexible connection from the other rod extending horizontally, and a pulley over which it extends to a point of operation, whereby the partition is held normally by the weight at one limit of its range of movement and may be moved to the other limit at will.

35 6. In a smoke-jack for round-houses, comprising a jack-stack terminating downwardly in a flaring hood for overhanging the locomotive to be served, said hood having its side-walls extending below the level of its end-walls and forming lateral guard flanges between which the locomotive smoke-stack advances to position to be served both the end-walls and the side-walls being terminated by outwardly-turned drip troughs, in combination with a fitting which closes the end of the drip troughs of the side-walls, said fitting having rigid with it a conduit which extends obliquely from under the end of the drip-trough of the adjacent end-wall to a point overhanging the drip-trough of the side-wall on which it is mounted for delivering the drip from the higher end-wall drip-troughs to the lower side-wall drip-troughs.

55 7. In a smoke-jack for round-houses, comprising a jack-stack terminating downwardly in a flaring hood for overhanging the locomotive to be served, said hood having its side-walls extending below the level of its end-walls and forming lateral guard flanges between which the locomotive smoke-stack advances to the position to be served, both the end-walls and the side-walls being terminated by outwardly-turned drip-

troughs; a fitting secured on the side-wall 65 flanges having rigid with it a conduit which extends obliquely from a point under the end of the adjacent end wall drip-trough to a point overhanging the drip-trough of the side-wall on which it is mounted.

5 8. In a smoke-jack for round-houses, comprising a jack-stack terminating downwardly in a flaring hood for overhanging the locomotive to be served, said hood having its side-walls extending below the level 75 of its end-walls and forming lateral guard flanges between which the locomotive smoke-stack advances to the position to be served both the end-walls and the side-walls being terminated by outwardly-turned drip-troughs; fittings constituting closures for the ends of the side-wall drip-troughs, having rigid with them conduits for conducting the drip from the end wall drip-troughs into the side-wall drip-troughs.

90 9. A smoke-jack for round-houses, comprising a downwardly-flaring mouth-piece or hood for overhanging the locomotive stack to be served, said hood having its side-walls extending below the level of the end-walls and flared outwardly, forming guard flanges between which the locomotive stack advances to position to be served; fittings secured to the outer surface of the ends of the guard flanges and extending up 95 into the angle between said flanges and the main body of said side-walls to stiffen the angles, and hanger rods connected to said fittings for suspending the stack.

100 10. In a smoke-jack for round-houses, in combination with a downwardly-opening jack stack having a flaring receiving mouth or hood and an up-and-down partition in such flaring mouth, mounted therein for lateral movement between the side walls of the 105 hood.

110 11. In a smoke-jack for round-houses, comprising a jack-stack terminating downwardly in a flaring hood for overhanging the locomotive to be served, said hood having its side walls extending below the level of its end-walls and forming lateral guard flanges between which the locomotive smoke stack advances to position to be served, the side walls being terminated by outwardly-turned drip-troughs and interior drip-troughs mounted on the inner side of the side-walls above the level of said outer drip-troughs, the side wall having an aperture 115 through which said inner drip troughs discharge into said outer drip-troughs.

120 12. In a smoke-jack for round-houses, comprising a jack-stack terminating downwardly in a flaring hood for overhanging the locomotive to be served, said hood having its side-walls extending below the level of its end-walls and forming lateral guard flanges between which the locomotive smoke

stack advances to position to be served, the side-walls being terminated by outwardly-turned drip-troughs at their lower edges, and the end-walls having mounted on their inner surfaces drip-troughs which extend through the side walls and over-hang and discharge into the outer drip-troughs of the side-walls.

Copies of this patent may be obtained for five cents each, by addressing the "Commissioner of Patents, Washington, D. C."

In testimony whereof, I have hereunto set my hand at Chicago, Illinois, this 5th day of October, 1914.

ORVILLE C. MANN.
